UNITED STATES PATENT OFFICE.

EDWIN M. LLOYD, OF SAN JOSE, CALIFORNIA, ASSIGNEE OF ONE-HALF TO THOMAS H. BALL, OF SAN JOSE, CALIFORNIA.

BURNER ATTACHMENT.

1,035,455.

Specification of Letters Patent. Patented Aug. 13, 1912.

Application filed April 8, 1911. Serial No. 619,265.

To all whom it may concern:

Be it known that I, EDWIN M. LLOYD, a citizen of the United States, residing at San Jose, in the county of Santa Clara and State of California, have invented new and useful Improvements in Burner Attachments, of which the following is a specification.

This invention relates to an attachment for lamp burners, and particularly pertains to a device for converting an ordinary tubular wick coal-oil lamp into an incandescent mantle lamp.

It is the object of this invention to provide a simple device which may be readily attached to and removed from the burner of the common oil burning lamp in which a circular wick is employed, such, for instance, as that known as the Rochester burner, and which device is so constructed and arranged that by its use the wick burning lamp will be converted into an incandescent mantle lamp.

A further object is to provide an attachment for accomplishing the above results, which may be readily applied to most burners of the Rochester type without alteration or removal of the burner, and which may be easily put in place or removed by the housewife or other users of the lamp.

By the use of this invention the wick lamp may be quickly converted into an incandescent lamp, or vice versa, thus adapting the lamp to a double purpose.

The invention consists of the parts and the combination and construction of parts as hereinafter more fully described and claimed, having reference to the accompanying drawings, in which—

Figure 1 is a vertical section of the invention as applied. Fig. 2 is a side elevation of the attachment constituting my present invention. Fig. 3 is an inverted plan view of same.

In the drawings A represents the bowl of a coal-oil lamp, which bowl may be of any suitable construction. Mounted on the bowl A is the ordinary tubular wick burner, which burner consists of a cylindrical housing 2 adapted to be threaded into the mouth of the lamp bowl A and which is surrounded by a perforated casing 3, and a wick advancing tube 4 on the interior of the housing 2, which is reciprocated vertically there-

may be operated by any suitable mechanism, not necessary to be here shown. The wick 5 surrounds a cylindrical tube 6, which is mounted in the lamp bowl A and extends therethrough, this tube opening to the bottom of the bowl A and terminating at its upper open end approximately on a level with the top of the burner housing 2, and is provided for the purpose of delivering a current of air to the inner upper ends of the burning wick 5, this center draft tube 6 being commonly employed in lamps of this character. Formed on the upper portion of the perforated casing 3 is a series of vertically extending spring members 7, disposed at suitable intervals apart around the casing, which members 7 are adapted to bear against the lamp chimney placed on the casing 3 and retain it in position, as is well known in oil burning lamps.

In the ordinary use of this lamp, the upper end of the wick 5 saturated with inflammable oil is advanced a short distance above the upper ends of the tube 6 and housing 2 and ignited, the flame thus generated throwing off a bright light by reason of the extended areas of wick surface and the free supply of air delivered thereto through the center draft tube 6 and the perforated casing 3. The fuel oil is supplied to the flame through the wick 5 by capillary attraction, as is well known.

The essence of my present invention resides in providing a cap 8, shown in detail in Figs. 2-3, which is peculiarly constructed and formed, and which is adapted to be placed upon and attached to the lamp burner just described by inserting it within the annularly disposed spring members 7, as shown in Fig. 1. The cap 8 is formed approximately in the shape of a frustum of a cone, is tubular, and open at both ends. The upper end of the cap is bent inwardly a short distance and is adapted to extend into the lower end of a mantle 9 which is supported above the opening in the upper end of the cap 8 in any suitable manner. The mantle 9 is of the ordinary type of incandescent mantles, and is here shown as supported on a wire bracket 10 which is mounted on the cap 8.

Mounted on the interior of the cap 8 is an annular baffle ring 11 which is spaced from the inner walls of the cap and concentric therewith, the ring 11 being connected to 110

the cap 8 by means of tangs 12, as shown in Figs. 1 and 2. This baffle ring 11 is of such inside diameter and is so positioned in the cap 8 that when the latter is placed in position on the burner the baffle ring will surround and closely contact with the outer peripheral surface of the housing 2 a short distance below the upper edge of the latter, as shown in Fig. 1.

10 As a means of providing a support for a lamp globe suitable to an incandescent burner, and which is not adapted to be supported in the clamp members 7 in the ordinary manner, I have devised a rim 13 which 15 can be placed over the clamp members 7, as shown in Fig. 1, and rests upon a flange 14 which is usually formed on the casing 3 at the base of the members 7. This rim 13 has a horizontal flange or ledge 15 formed 20 on its outer face on which a globe 16 is adapted to rest.

The parts being placed in position on the burner, as shown in Fig. 1, and the wick 5 ignited, a current of air is caused to enter 25 the perforated casing 3 below the rim 13, which current passes upward around the housing 2 until it strikes the ring 11, whereupon it is deflected against the inner inclined walls of the cap 8, from whence it is again 30 deflected so as to strike the flame on the wick in substantially a horizontal direction. At the same time, a current of air is delivered to the flame through the center draft-tube 6, this latter current being directed 35 laterally through a perforated cap 17 in the upper end of the tube 6, and these currents meeting head on at the point of combustion convert the normal yellow flame of the burning wick into a blue flame of intense heat.

40 This hot flame rising into the interior of

the mantle 9 heats the latter to a state of incandescence, with the result that an intensely brilliant light will be projected therefrom.

From the foregoing it will be seen that I have provided a simple attachment by which a center draft tubular wick oil-burning lamp may be converted into an incandescent lamp, which attachment may be removed at any time and the lamp restored to its normal form.

The perforated cap 17 is closed on its upper end so as to direct the current of air passing through the center draft-tube 6 in a horizontal direction, the perforations being formed in the side walls of the cap in any suitable manner so as to distribute the air evenly to the flame.

Having thus described my invention, what I claim and desire to secure by Letters Patent is:

The combination with a burner having outer and inner wick inclosing tubes and a gallery with inclosing elastic members, of an upwardly convergent, open ended cone, having its base removably fitted within the elastic members and its upper open end registering with the upper end of the wick, a perforated concavo-convex baffle ring located within the cone with its inner periphery fitting the housing of the burner, and a flanged chimney supporting rim exterior to the elastic members.

In testimony whereof I have hereunto set my hand in the presence of two subscribing witnesses.

EDWIN M. LLOYD.
